TUBE LOCK FOR GUNS

William Summerbell, Washington, D. C.; Edith May Summerbell executrix of said William Summerbell, deceased

Application February 12, 1947, Serial No. 727,984

(Granted under the act of March 3, 1883, as amended April 30, 1928; 370 O. G. 757)

5 Claims. (Cl. 89—17)

1

The invention described herein may be manufactured and used by or for the Government for governmental purposes, without the payment to me of any royalty thereon.

This invention relates to an improved means for locking the tube of a gun to the breech ring.

An important object of the invention is to facilitate removal of the tube or barrel of a large caliber gun in the field and allow substitution of another barrel without having to transport the entire gun to some distant point.

While the invention is adaptable to various types of guns, it is, in the present instance, applied to the 90 mm. gun but it may readily be applied to guns of larger or smaller caliber. It is a particular aim of the invention to embody such a device in a simple and compact form, making it exceptionally important for use on guns of larger caliber. Likewise, it is sought to simplify and make more rapid the assembly and disassembly of the barrel and breech ring.

The breech end of a gun tube is segment-threaded for attachment to the breech ring which is screwed on the end of the tube. At present, the tube and breech ring are locked together at the top by a tube locking key which is secured in place by means of screws, a stop and a spring mounted above the key, and both a screw driver and a wrench are required to raise the key so that the barrel may be unscrewed and withdrawn from its engagement with the breech ring. These locking means, however, are not easily accessible unless other parts of the gun mounted above the breech are first removed.

In my invention the presently used means for securing the locking key are eliminated, and the locking key or barrel lock is secured and controlled from the open breech ring by simple and easily accessible means mounted on the said breech ring.

In order to avoid injury to personnel and damage to the gun, great caution is necessary in disassembling a gun tube from a breech ring since the tube must be turned exactly $\frac{1}{8}$ of its circumference to permit the interrupted threads of the bayonet joint to pass each other. Clearing of the threads is made certain in my invention by means which limit rotation of the tube, as will be hereinafter described and pointed out.

Another object of my invention is its effect in reducing the torque of the gun without the necessity of employing bolts or other restraining means.

Additional objects, advantages and features of the invention reside in the construction, ar-

2

rangement and combination of parts involved in the embodiment of the invention, as will be understood from the following description and accompanying drawings, forming part of the specification, wherein similar numbers are used to designate like parts throughout the specification and drawings.

In the drawings:

Figure 1 is a perspective view of the breech ring and tube assembly of a gun, showing the location of the locking mechanism,

Figure 2 is a longitudinal section through the breech ring, taken on the line 2—2 of Figure 1.

Figure 3 is a transverse section through the barrel lock and gun tube facing the breech end of the gun, taken on the line 3—3 of Figure 2.

Figure 4 is a perspective view of the barrel lock,

Figure 5 is a section taken on the line 5—5 of Figure 2,

Figure 6 is an elevation to an enlarged scale of the cam shaft,

Figure 7 is an elevation of the face of the cam shaft adjacent the breech ring,

Figure 8 is a transverse section through the cam shaft, taken on the line 8—8 of Figure 6,

Figure 9 is an elevation of the face of the cam shaft adjacent the barrel lock,

Figure 10 shows the indexing means on the rear face of the breech ring and on the face of the cam shaft as they appear within the rearward opening of the breech ring.

Figure 11 is an exploded perspective view of the segment-threaded connection between the breech block and the tube as well as the recesses in the tube by which it is limited in rotation within the breech ring and locked therein in firing position, and, Figs. 12 and 13 are sectional detail views taken in planes identified by lines 12—12 and 13—13, respectively, of Fig. 11.

The numeral 10 shows a well known form of a breech ring as presently used on a 90 mm. gun, into which the barrel or tube 11 of the gun is fitted, the rear portion of the said breech ring being generally rectangular. The breech block has been omitted since its details are well known and form no part of the invention.

The breech end of the tube 11 is provided with interrupted threads 12 which engage similar threads 12a in the interior of the breech ring 10 in a conventional manner. The said breech ring 10 is locked to the tube 11 by means of a lock shaft 13 slidably mounted in a vertical bore 14 in the said breech ring 10 near its forward or muzzle end. The said lock 13 is

formed with a foot 15, Fig. 4, functioning as a key to engage within a recess 16 in the tube 11. See Fig. 11. A recess 17 having the same width as the foot 15 is provided in the breech ring 10, to open through the bore therein and the muzzle face of the breech ring to accommodate the foot when it is in a raised position during the removal and insertion of the tube 11. A circumferential groove 18 equal in length to the circumferential extent of threads 12 and 12a, or one-eighth of the circumference of the tube, and of approximately one-half the depth of the recess 16, is provided in the surface of the tube 11 immediately adjoining and forming a continuation of recess 16 to define the limit of rotation of the tube 11 when the said segment threads are being disengaged in disassembly.

The breech ring 10 is bored and counterbored longitudinally to provide a bore 19 having successive portions of different diameters and extending from its rearward or breech face 20 to and opening into the vertical bore 14, the axes of the said bores 14 and 19 being at right angles to each other. Another vertical bore 21 is provided in the said breech ring 10 adjacent its rearward face 20, perpendicular to and communicating with the bore 19.

A cylindrical cam shaft 22 is rotatably mounted in the bore 19. The said shaft is formed with two annular flanges 23 and 24 at one end to have a smooth fit within the largest diameter portion of the bore 19 adjacent the rearward face 20. The annular groove 25, defined by and lying between flanges 23 and 24, is provided with a plurality of cylindrical recesses or pockets 26, 27, and 28, Fig. 8, of the same diameter as the bore 21. In assembly of the shaft 22 within the bore 19, these pockets 26, 27 and 28 will lie successively in the longitudinal or fore and aft plane of the bore 21 during rotation of the said shaft 22, and become in effect a continuation of the said bore 21. The diameter of the body of the shaft 22 is increased immediately adjacent the shoulder 24 and again at its forward end to provide bearing surfaces for the shaft within the bore 19. A cylindrical eccentric trunnion or cam 29 is formed on the end of the shaft 22 farthest removed from the shoulders 23 and 24 to engage within a notch or groove 30 in the lock 13.

The face 31 of the shaft 22 adjacent the shoulder 23 is provided with three radial screw-driver slots 32, 33 and 34 of a depth greater than the width of the shoulder 23 whereby a screw driver blade may be inserted to lift a plunger 35 mounted in the bore 21, the said plunger being urged downwardly by a spring 36 and retained in the bore 21 by a plug 37, and dimensioned to fit slidably between the shoulders 23 and 24 of the shaft 22.

The rear face 20 of the breech ring 10 is suitably engraved upon its surface in such manner that the position of the lock foot 15 will be indicated by an index 38 engraved on the face 31 of the shaft 22, as shown in Figure 10.

The tube 11 is locked to the breech ring 10 by engagement of foot 15 within recess 16. When shaft 22 has been rotated to move foot 15 to this position, index 38 points to the inscription "Tube Locked." Plunger 35 is then located in pocket 26 and releasably held therein by spring 36. To remove the barrel or tube 11 from the breech ring 10 a screw driver is inserted in the slot 32 and pressed against the bottom of the plunger 35, forcing it upward within the bore 75

21 against the resistance of the spring 36 until the said plunger has been released from its engagement within the pocket 26. The shaft 22 is then revolved 90° in a counterclockwise direction by means of the screw driver until the arrow 38 points to the inscription "Tube Unlocked," indicating that foot 15 has been lifted until its bottom surface is a little above the bottom of the recess or channel 18 to permit rotation of the tube 11 through 45° and thereby separate the threads of the tube and breech ring. The pocket 27 is now in alignment with the bore 21 and the plunger 35 being released from the pressure of the annular groove 25 moves into the pocket 27 under the action of spring 36.

After shaft 22 is rotated to its "Tube Unlocked" position, as just described, tube 11 may be unscrewed to disengage the interrupted threads of the tube and breech. The extent of this rotation is precisely determined and limited by engagement between foot 15 and the end wall 39 of recess 18. Thus when rotation of the tube is stopped as just described it is known that the interrupted threads are entirely disengaged. However, the tube cannot be axially withdrawn at this time because the bottom of foot 15, has only a small clearance radially outwardly of the bottom of recess 18.

The screw driver is now inserted in slot 33 and the plunger 35 is again forced up into the bore 21. The shaft 22 is again revolved counterclockwise until the arrow 38 points to the "Tube Removed" inscription whereupon the said plunger drops into the pocket 28, all in the manner heretofore described. Revolving the shaft 22 has caused the foot 15 to be lifted clear of groove 18, shoulder 39 and threads 12. The tube 11 is now free for axial withdrawal from the breech ring.

To assemble a new tube, the indicating arrow will point to the inscription "Tube Removed," and the tube is inserted into the breech ring in the usual manner. Thereupon, all of the heretofore described movements will be repeated but in reverse order, the shaft being revolved clockwise, until, upon completion of the operation, the arrow will point to the "Tube Locked" inscription, indicating that the foot 15 is securely engaged within the recess 16 of the tube 11. In this operation, when the index 38 is moved to "Tube Unlocked" position wherein foot 15 is just a little above or radially outwardly of the bottom of recess 18, rotation of the tube to a position wherein the interrupted threads are fully engaged, is determined when foot 15 abuts against the end of recess 16. The foot may then be moved into the recess, by operation of index 38 to "Tube Locked" position to positively prevent all rotation of the tube relatively to the breech block.

It is to be understood that the form of my invention, herewith shown and described, is to be taken as a preferred example of the same, and that various changes in the shape, size and arrangement of parts may be resorted to without departing from the spirit of my invention or the scope of the subjoined claims.

Having thus described my invention, I claim:

1. The combination with a gun tube and separable breech ring therefor, a cam shaft revolvably mounted within said breech ring, said cam shaft being provided with camming means at one end and two annular shoulders at the opposite end, a lock shaft provided with a foot to engage and lock said gun tube to said ring and a recess to

engage the camming means of the said cam shaft whereby said foot is freed from its locking engagement with the gun tube when said cam shaft is rotated, plunger means cooperating with circumferentially spaced recesses in said cam shaft between said shoulders whereby said cam shaft may be held in a plurality of rotative positions, and indexing means between said ring and cam shaft to indicate said positions.

2. The combination recited in claim 1, there being a plurality of radial slots in the end of said cam shaft each said slot having a depth greater than the thickness of the adjacent shoulder whereby each slot opens into a respective one of said spaced recesses and whereby a bladed tool may be inserted into any slot aligned with said detent means to release the detent means from a recess and thereafter turn said cam shaft to a new determinable position.

3. In a device for locking a gun tube within its breech ring, said tube having interrupted threads on its breech portion arranged to engage with a correspondingly threaded bore in said ring when said tube is inserted axially into said bore in a first position and rotated through a predetermined angle to a second position, a lock shaft fitting a radial bore in said ring and slideable therein, said lock shaft having a foot on its inner end arranged to enter a recess in said tube when said tube is in said second position only, to thereby lock said tube against rotation, there being a circumferential groove in the exterior surface of said tube, opening at one end into said recess and of less depth than said recess, said groove extending through said predetermined angle, a cam shaft journaled in said ring and having an eccentric portion engaging said shaft to move the same radially as said shaft is turned, and means to positively position said cam shaft to locate said foot at the level of the bottom of said groove, said eccentric portion comprising an eccentric pin on the end of said cam shaft and engaged with a transverse notch in said lock shaft, whereby rotation of said cam shaft positively moves said lock shaft radially in its bore, and detent means associated with said cam shaft to yieldingly position said shaft in a selected one of three rotative positions corresponding to positions of said foot (1) in said recess, (2) at the level of the bottom of said groove and (3) at the level of the exterior surface of said tube.

4. In a gun tube positioning and locking mechanism for a gun having a tube and breech ring separable by limited rotation of said tube from

5

a second to a first position, followed by axial withdrawal from said ring, locking means carried by said ring for movement radially of said tube from a first adjustment free of said tube to successive second and third adjustments radially inwardly of said first adjustment, means fixed with said tube and cooperating with said locking means when the latter is in said second adjustment, to limit rotation of said tube between first and second positions, and means fixed with said tube and cooperating with said locking means only when said locking means is in third adjustment to positively lock said tube in said second position, adjusting means carried by said ring and operable to selectively move said locking means to first, second and third adjustment, and securing means carried by said ring to releasably hold said locking means in selected adjustment.

5. A mechanism as in claim 4, said adjusting means comprising a shaft journaled in said ring and having three positions of rotational adjustment and having one end exposed, there being flats on said one end corresponding to said three adjustment positions of said shaft and locking means, said securing means comprising a spring-pressed plunger mounted in a hole in said ring to engage a selected one of said flats, there being radial slots in said one end of the shaft, each slot corresponding to and opening into a respective flat beneath said plunger, whereby a blade may be inserted into the slot beneath said plunger to raise the same and thereafter turn said shaft and move said locking means to a new position of adjustment.
